UNITED STATES PATENT OFFICE.

ERICH BARTH, OF CHEMNITZ, GERMANY.

CIRCULAR-KNITTING MACHINE.

Application filed May 12, 1923. Serial No. 638,671.

To all whom it may concern:

Be it known that I, ERICH BARTH, a citizen of the German Republic, residing at Chemnitz, Germany, have invented certain 5 Improvements in Circular-Knitting Machines, of which the following is a specification.

In the ordinary circular knitting machines, a diagonal pattern is produced by 10 means of a differently coloured patterning thread or threads. The thread is sometimes fed through a rotatively displaced guide which changes its position for each revolution of the machine. Patterning wheels are 15 also employed which hold the respective needles in a position to catch the thread and which are either advanced or retarded in order to make the pattern run diagonally on the fabric.

20 In either case the angle of adjustment of the patterning elements is limited so that a continuous spiral pattern can only be produced by carrying the thread loosely at the back of the fabric from one pattern stripe 25 to another. This involves a considerable waste of material, and the arrangement does not lend itself to the use of different colours for adjacent pattern stripes.

The object of the present invention is to 30 adapt the circular knitting machine for producing continuous diagonal patterns without any transfer of thread from one stripe to the other, and the invention consists in arranging the guide for the pattern thread 35 stationary, and adapting the needle cylinder for rotary adjustment, a periodic displacement of the cylinder being brought about by means of the cam ring drive. As there is nothing to limit the displacement of 40 the cylinder, the pattern can be carried on continuously in a spiral fashion, and differently coloured threads may be used for the individual stripes.

45 Fig. 1 of the accompanying drawings represents a vertical section of the device,

Fig. 2, a plan of the same, and

Fig. 3, a diagrammatic view illustrating the formation of the pattern.

50 Figs. 4, 5 and 6, are diagrams showing the old system of patterning, and

Fig. 7, a diagram showing the system according to the present invention.

The needle cylinder *a* is carried by a ring

c which is rotatably guided in the machine frame *b* and which is formed integrally with 55 or connected to a ratchet wheel *n* having as many teeth as there are needles in the cylinder. The cam elements *d* are carried by a ring *e* which is driven in the usual manner by means of a bevel gear *f*. The cam ring revolves once for each revolution of the gear *f*. Keyed to the shaft of the latter is a ring *g* on which there is a tappet *h*. A double- 60 armed lever *l* carries at one end a pivoted pawl *m* which engages the teeth of the 65 ratchet wheel *n*. The other end of the lever *l* is held by a spring against a roller *k* which is carried by a plunger. The latter is held in a guide *i* and is arranged so as to be operated by the tappet *h* at each revolution of 70 the cam ring for advancing the wheel *n* one or more teeth according to requirements, the needle cylinder being adjusted accordingly. A detent pawl *o* controlled by a 75 spring *p* prevents retrograde movement of the elements.

The patterning thread is held by guides *q* (Fig. 3) which are fitted in a head *r* in the usual manner. However, while the head *r* is ordinarily displaced for producing the 80 diagonal pattern, in this case it is held stationary, as the desired effect is produced by the rotary displacement of the needle cylinder. Fig. 3 shows the formation of the pattern by a displacement of the needles to 85 the right by one needle space for each course. The displacement can be carried on regularly throughout the length of the fabric which will have the appearance shown more clearly in Fig. 7. It will be noticed that 90 there are no loose threads at the back of the fabric as in the examples given in Figs. 4 and 6, the loose thread being shown at *t*. This is unavoidable in the ordinary machines unless the pattern is run in zig-zag 95 as shown in Fig. 5.

I claim:—

1. In a circular knitting machine, the combination with a rotatable cam ring and with a driving gear for operating the same, 100 of a stationary guide for supplying the patterning thread, a rotatable needle cylinder, and connections between the driving gear and the cylinder for rotating the same intermittently so as to produce a diagonal pattern, substantially as set forth.

2. In a circular knitting machine, the ratchet wheel for turning the cylinder, a combination with a rotatable cam ring and with a driving gear for operating the same, of a stationary guide for supplying a patterning thread, a rotatable needle cylinder, a ratchet wheel connected to said cylinder, a spring-pressed pawl cooperating with said pawl connected to said driving gear so as to operate the plunger and rotate the cylinder intermittently for producing a diagonal pattern. 10

ERICH BARTH.
